UNITED STATES PATENT OFFICE.

THOMAS S. REED, OF BRIDGEPORT, CONNECTICUT, ASSIGNOR TO THE
BRIDGEPORT BRASS COMPANY, OF SAME PLACE.

ELECTRICAL CONDUCTOR.

SPECIFICATION forming part of Letters Patent No. 276,880, dated May 1, 1883.
Application filed July 15, 1882. (No model.)

To all whom it may concern:

Be it known that I, THOMAS S. REED, of Bridgeport, in the county of Fairfield and State of Connecticut, have invented a certain new and useful Improvement in Electrical Conductors, of which the following is a specification.

My improvement relates to the flexible electrical conductors which are commonly used in conjunction with telephone-receivers, and with various analogous articles requiring to be moved from place to place. Such electrical conductors have commonly been made of very fine, delicate wires enveloped in a braided covering.

The principal object of my invention is to provide an electrical conductor, for use in connection with telephones, which will not be liable to kink and become tangled when slackened, and in which the fine, delicate wires shall not be liable to injury because of the stretching of their covering, as a braided covering will do.

The improvement consists in a new article of manufacture—namely, an electrical conductor consisting of a number of fine metal wires or filaments laid side by side in approximately the same plane, and a flat fabric incasing the same, and having longitudinal threads incorporated into it and serving as longitudinal stays or braces.

In the accompanying drawings, Figure 1 is a partly-sectional side view of an electrical conductor embodying my improvement, and Fig. 2 is a sectional view of a tip which is applied to the ends of its branches.

Similar letters of reference designate corresponding parts in both figures.

A designates a number of fine metal wires or filaments, made, for instance, of copper or brass. Preferably I use what is termed "tinsel," an article consisting of a thread having a flat metal wire or filament wound spirally around it, as this is susceptible of being bent and stretched a great deal without breaking.

B designates a covering made in the form

of a flat tape or fabric and enveloping the wires A. It may be made of cotton or other suitable material, and may be woven. In any case it will have longitudinal or warp threads incorporated into it for preventing it from stretching. This may be woven or formed over or upon the wires A; or it may be made in the form of a pocket into which the wires may be slipped; or, indeed, it may be made in a flat fabric and sewed around the wires.

If desirable for any special purposes, india-rubber cloth or analogous material may incase the wires A and be surrounded by the covering. Near the ends the covering is divided longitudinally to form two branches each containing half the wires. This may be done in the manufacture of the covering, or it may be manufactured in one continuous and uniform piece, to be subsequently cut and sewed to form the branches. The wires are laid side by side in approximately the same plane, and at the ends of the branches have attached to them pins C, which are adapted to be inserted and secured in the binding-posts of telephone-receivers or other articles.

To impart a finished appearance to the ends of the branches I preferably incase them in tips of sheet metal, D. These tips will preferably be made of two sections, having their edges overlapped so as to secure them together. The pins C pass through semicircular recesses formed in these sections of the tips.

What I claim as my invention, and desire to secure by Letters Patent, is—

As a new article of manufacture, an electrical conductor, consisting of a number of fine metal wires or filaments laid side by side in approximately the same plane, and a flat fabric incasing the same, and having longitudinal threads incorporated into it and serving as longitudinal stays or braces, substantially as and for the purpose herein described.

THOMAS S. REED.
